THOMAS P. ARCHER AND JOHN B. FLYNN, OF DETROIT, MICHIGAN, ASSIGNEES TO
TERNSTEDT MANUFACTURING COMPANY, OF DETROIT, MICHIGAN, A CORPORATION
OF MICHIGAN

LATCH

Application filed March 16, 1929. Serial No. 347,494.

This invention relates to a latch and more particularly to a latch for refrigerators. It is common knowledge that the portion of the refrigerator door opposite the latch handle soon becomes marred and soiled through contact with the operator's hand. It is one of the objects of this invention to obviate this worn or marred area on the refrigerator door by means of an extension of the latch support plate which extension serves as a shield to prevent contact between the operator's hand and the surface of the refrigerating door.

It is also an object of this invention to present a latch with a positive lock for the bolt.

In the latch in which the handle is retracted against the expansive action of the spring, it often happens that the handle is allowed to fly freely back which not only results in the denting and marring of the lock casing, but also produces undesirable noise. Hence, it is an object of this invention to provide a latch handle with a resilient bumper arranged to engage the casing of the latch.

It is the further object of this invention to present a latch having a unitary stamped metal plate and casing for the latch mechanism.

In the plunger type of latch, it is desirable for esthetic and operative reasons to have as many of the operating parts as possible hidden from view. Hence, this invention contemplates a latch in which the bolt may be completely retracted without projecting through the rear of the casing.

In the drawings:

Fig. 1 is a front elevation of the latch.

Fig. 2 is a front elevation of the latch partly broken away and with the internal mechanism of the latch in dotted lines.

Fig. 3 is a longitudinal-sectional view of the latch and striker attached to their supports which are in dotted lines.

Fig. 4 is a section along the line 4—4 of Fig. 3 when the latch bolt is locked.

Fig. 5 is a section similar to section 4 when the latch bolt is unlocked.

Fig. 6 is a section along the line 6—6 of Fig. 1 when the latch bolt is unlocked.

Fig. 7 is a detailed view of the lock tumbler cylinder.

Fig. 8 is a perspective of the latch bolt.

Fig. 9 is a section through the bolt guide member.

Fig. 10 is a detailed view of the bell crank end of the latch handle.

Referring more particularly to the drawings, the latch may be generally designated 1, the striker 2, and in this instance the supports to which the latch and striker are secured are respectively the door 4 and the door frame 5. The latch consists of the support plate 6, the casing 7, and the apertured ears 8. The ears 8, the casing 7, and the support plate 6 are unitary and stamped from a single piece of metal.

As shown in Fig. 1, the plate 6 has the extension 9. The handle 10 is pivotally mounted between the ears 8 by means of the pin 11. It will be seen that the extension 9 of the support plate 6 is sufficiently large to serve as a shield against which the hand of the operator contacts when the handle 10 of the latch is grasped to actuate the latch. This shield portion 9 therefore takes the place of what would otherwise be the painted portion of the latch support which would readily show the wear caused by contact with the operator's hand, hence, the shield portion 9 prevents the formation of any unsightly worn portion on the face of the latch support.

The internal mechanism of the latch consists of the bolt 12, the guide 13, the spring 14, the spring support rod 15, and the lock mechanism 16.

The guide 13 consists of the two parallel wall portions 21, each of which has a projecting apertured lug 22, and is arranged to fit within the casing 7 so that the lugs 22 coincide with the ears 8. The guide has the positioning lugs 23 which are arranged to abut against the latch support as at 24, (Fig. 3) and the annulus 25 which has the diametrically opposed recesses 26 and 27 and the projecting lug 28. The bolt 12 has a sliding fit within the guide 13 and, as shown in Fig. 8, is flat and has the bifurcated end 43 in which is rotatably mounted the roller 44 by

means of the pin 45. The bolt has the recessed portions 42 and 47, the purposes of which are explained below, and the holes 48 and 49 for the spring support rod 15 which 5 has a sliding engagement with the bolt. The spring support rod 15 has the enlarged head 38 which serves as a spring abutment and the riveted lug end 39 which fixes the rod 15 to the casing. The spring 14 is carried by 10 the rod 15 between the abutment 38 and the bolt end lug 29. This arrangement of the internal latch mechanism permits the bolt to be completely retracted without projecting through the rear of the casing.

15 The handle is of the bell crank type having the spaced roll-backs 17 and the hole 18 in which is cemented or otherwise secured the rubber bumper 19 which resiliently engages the casing 7 as at 20. The bumper prevents 20 the handle from marring the casing and prevents any noise when the handle is allowed to fly freely back into position. The handle is pivotally mounted between the ears 8 and between the lugs 22 of the guide 13 by means 25 of the pin 11 which also serves to fix the guide 13 within the casing. The roll-backs engage the lug 29 of the bolt, one on each side of the spring support bar, and when the handle 10 is actuated, retract the bolt 12 against the 30 pressure of the spring 14. The bolt 12 slidably engages the spring support rod 15. The casing has the struck-in lug 51 which serves as a guide for the bolt.

The lock cylinder is carried by the annulus 35 25 of the guide 13 and has a recess therein for the tumbler 31, and has the projecting lug 32. The tumbler 31 may be any well-known type of spring pressed cylinder lock tumbler which projects into the recess in the 40 annulus 25 to interlock the lock cylinder and annulus 25. By inserting the key 37 in the key hole 36, the tumbler 31 is retracted and the lock cylinder is free to turn in the annulus 25. The lock cylinder has the arcuately recessed annulus 33 with the shoulders 34 and 35 (Fig. 7). By referring to Fig. 7, 45 it will be noticed that the shoulders are not diametrically disposed. The cylinder has the recess 36 for the key 37.

50 As shown in Figs. 2, 3, and 4, the lug 32 of the lock cylinder squarely abuts the shoulder 41 of the bolt, and hence the bolt is in locked position. To unlock the bolt, the lock cylinder is turned 180° by means of the key 37 till the shoulder 34 of the annulus 33 of the lock cylinder abuts the lug 28 of the 55 guide member and this places the lug 32 of the lock cylinder in the position shown in Fig. 5. The bolt may then be retracted 60 (Fig. 5) till the lug 32 enters the recess 42 of the bolt 12. Spring 14 is preferably so tensioned that it is completely contracted just before the lug 32 engages the bolt 12 in the recess 42 and the bolt abuts against the end 65 of the rod 15.

What we claim is:

1. In a latch for a refrigerator door, or the like, of the type having a reciprocable bolt, a composite casing for the said bolt consisting of an outer stamped member and an inner die-cast member arranged to fit within the said outer member and to serve as a guide for the said bolt, the said outer member serving to hold the said inner member in position. 70

2. In a latch for a refrigerator door, or the like, having a reciprocable bolt and a handle therefor, a composite casing consisting of an outer stamped member and an inner die-cast member arranged to fit nicely within the said outer member to guide the said bolt and to support the said handle, the outer member arranged to hold said inner member in position. 75

3. In a latch for a refrigerator door, or the like, a bolt having a flange at one end, a casing, a guide rod for the bolt, and a handle pivotally mounted on the said casing having a plurality of roll-backs straddling the said guide rod and arranged to engage the said flange to retract the said bolt. 80

4. A latch for a refrigerator door, or the like, having in combination a reciprocable apertured bolt with an apertured flange at one end, a casing, a guide rod arranged to slidably engage the said bolt and flange, and a handle mounted on the said casing having a roll-back arranged to engage the said flange to retract the said bolt. 85

5. A latch for a refrigerator door, or the like, having in combination a reciprocable apertured bolt with an apertured flange at one end, a casing, a guide rod arranged to slidably engage the said bolt and flange, a handle pivotally mounted on said casing having a plurality of roll-backs straddling said rod and arranged to engage the said flange to retract the said bolt. 90

In testimony whereof we have affixed our signatures. 100
